UNITED STATES PATENT OFFICE.

EARL T. BENNINGTON, OF COLONIAL HEIGHTS, OHIO.

RAIL COUPLING.

Application filed November 29, 1920. Serial No. 427,111.

To all whom it may concern:

Be it known that I, EARL T. BENNINGTON, a citizen of the United States, residing at Colonial Heights, in the county of Cuyahoga and State of Ohio, have invented a certain new and useful Improvement in Rail Couplings, of which the following is a full, clear, and exact description.

This invention relates to rail couplings for 10 overhead carrier systems, such, for example, as monorail systems which have overhead tracks with flanges that support the wheels of trolleys or carriers.

The chief object of the invention is to provide 15 a coupling which effectively joins together two adjoining rails, and which holds them in absolute alignment without liability of one rail twisting with reference to the other.

20 The invention may be briefly summarized as consisting in certain novel details of construction and combinations and arrangements of parts which will be described in the specification and set forth in the appended 25 claims.

In the accompanying sheet of drawings, Fig. 1 is a side view of the two clamping plates of the coupling omitting the clamping screws which are employed therewith; 30 Fig. 2 is a similar view but showing the opposite side of the coupling to that seen in Fig. 1; Fig. 3 is a top plan view of the same; Fig. 4 is an end view of the complete coupling showing one of the rails in 35 section; and Fig. 5 is a transverse sectional view substantially along the line 5—5 of Fig. 1, looking in the direction indicated by the arrow.

40 In this instance the rails to be joined are of the section shown at 10 in Fig. 4, that is to say, the rails are T-shaped in cross section with an upper head 10^a, a web 10^b, and lower flanges 10^c along which the wheels of the trolleys are adapted to pass. However, 45 it is not essential to my invention that the rails have the shape herein shown.

The coupling includes two clamping members 11 and 12, which are preferably though not necessarily in the form of stampings. 50 These members are of such length that they will overlap the abutting or adjoining ends of two adjacent rails and will extend for a suitable distance, such as eight or ten inches, on each side of the joint so as to effectively 55 support the free ends of the rails, which free

ends are of necessity located some distance from the main rail supports which engage the rails at intervals and support them.

This coupling is of a design such that it 60 envelops the heads of the two rails and clamps them tightly in position, and also extends downward and securely clamps the webs of the rails so as to hold them in complete alignment. To this end the clamping plates 11 and 12 are provided with outwardly bowed portions 13 which extend over the top downwardly around the sides, and to an extent inwardly under the heads of the two rails forming in effect a head receiving compartment with head engaging shoulders or 65 abutments 14, formed by giving the plates an inward bow or depression which extends the full length of both clamps. From these inward depressions or bowing the plates extend downward with convex curvature, 70 and at their lower ends are curved inwardly to form clamping jaws 15 which are designed to engage opposite sides of the webs of the two rails just above their flanges 10^c.

The plate 11 has upstanding arms 16, there 75 being in this instance three of these arms, each having at its base a slot 17. Similarly the plate 12 has a corresponding number of arms 18 which are narrower than the arms 16 and are in this instance, though not necessarily, bifurcated. These arms 18 extend through the slots 17 forming crossed 80 portions of such a nature that when the arms 16 and 18 are pressed together and secured together as by means of screws 19, the two plates fulcrum at the points where the arms 18 pass through the slots at the bases of the arms 16, producing a strong 85 inward pressure of the jaws 15 on the webs of the two rails. Preferably the screws 19 pass through elongated openings in the bifurcated arms 18 and through tapped openings in the arms 16, as clearly shown in the 90 drawings.

100 Additionally the plates carry means for solidly clamping the heads of the two rails down against the inwardly bowed shoulder forming portions 14. To this end the plate 12 is provided between the arms 16 and also at the extreme ends with straps which extend upwardly as shown at 20, and then laterally or at right angles over the heads of the two rails, as shown at 21, the extreme or free ends of these straps being notched 105 as best shown at 22 in Fig. 3. Likewise the 110

opposite clamping plate 11 has corresponding fingers or straps 24 which are much narrower than the straps on the plates 12, these straps or fingers 24 extending into the notches 22 and provided at their upper ends with T-shaped heads 25 which overlie the free ends of the straps first mentioned. The portions 21 of the straps on the plate 12 have openings which receive clamping screws or bolts 26 which are directly above and in line with the center line of the heads of the two rails. These screws or bolts are provided with nuts 27 located beneath the portions 21 of the straps on the plate 12 between the upright portions of the straps on both plates so as to be held thereby from turning when the screws or bolts 26 are turned. The result is that when the screws or bolts 26 are turned down, their lower ends bear solidly onto the heads of the two rails, holding them down against the shoulders 14 of the clamping plates and effectively preventing endwise movement of the rails in the coupling. In practice there is a tendency of the wheels of motor driven carriers to slide the rails in the couplings; but this tendency is wholly overcome by this construction. At the same time that the screws are turned down of course the nuts 27 exert an upper pressure on the upper horizontal portions 21 of the straps of the plate 12, but this pressure is resisted by the T-shaped heads on the straps 24, which prevent upward bending of the said portions 21 of the straps.

With this construction the heads of the rails are very securely held or clamped, and at the same time the jaws at the lower edges of the clamping plates hold the webs of the two rails in alignment so that not only are the rails securely held together, but they are prevented from twisting or turning relatively so that the flanges of one rail cannot protrude or extend beyond, above or below the flanges of the other rail, with the result that the wheels of the trolleys can travel from the flanges of one rail to the flanges of the other without shock. Additionally the coupling can be applied very readily and can be inexpensively formed from stampings of suitable thickness to form a coupling of desired rigidity.

Having described my invention, I claim:

1. A coupling for two adjoining overhead rails comprising clamping members adapted to extend over and to produce clamping pressure down on the heads of the rails, and having detachably connected portions for engaging the webs of the rails.

2. A coupling for two adjoining overhead rails comprising a pair of clamps adapted to be connected together over the heads of the rails, and having means adapted to produce clamping pressure down on the heads

of the rails and having also portions adapted to extend down along and to exert clamping pressure on the webs of the rails.

3. A coupling for two adjoining overhead rails comprising a pair of clamps having crossed portions adapted to extend above the upper portions of the rails, and clamping jaws adapted to extend down along the webs of the rails, means for producing clamping pressure down on the heads of the rails, and means for bringing together the upper portions to cause the jaws to exert clamping pressure on the webs.

4. A coupling for a pair of adjoining overhead rails comprising clamping means having a rail head receiving portion comprising detachably connected members with shoulders which the lower portions of the heads are adapted to engage, and means for clamping the heads against the shoulders.

5. A coupling for a pair of adjoining rails comprising clamping means having a rail head receiving portion with head engaging shoulders adapted to be engaged by the lower portions of the heads, means for clamping the heads down against the shoulders, and detachably connected members for engaging opposite sides of the rail webs to hold them in alignment.

6. A coupling for a pair of adjoining rails comprising a pair of clamps having head receiving portions with lower head engaging shoulders, jaws beneath said portions for engaging the webs of the rails, arms above the first named portions adapted to be drawn together to cause the jaws to engage the rail webs, and means for forcing the heads against said shoulders.

7. In a coupling for two rails of an overhead trackway, a pair of clamps having head receiving portions with crossed arms above the same and web engaging jaws beneath the same, means for clamping the arms together, and means for forcing the heads of the rails against the lower parts of the head receiving portions.

8. In a coupling for two rails of an overhead trackway, a pair of clamps with means for causing portions thereof to firmly engage portions of the rails to hold them in alignment, and means for engaging the heads of the rails to hold them against endwise movement.

9. In a coupling for two rails of an overhead trackway, a pair of clamps with means for causing portions thereof to firmly engage portions of the rails to hold them in alignment, and means comprising a plurality of holding members adapted to engage the heads of the rails to hold them against endwise movement.

In testimony whereof, I hereunto affix my signature.

EARL T. BENNINGTON.
